UNITED STATES PATENT OFFICE.

ELI G. IVEY AND MORGAN MCMICHAEL, OF BUENA VISTA, GEORGIA.

FLOOD-GATE.

SPECIFICATION forming part of Letters Patent No. 439,517, dated October 28, 1890.

Application filed July 18, 1890. Serial No. 359,137. (No model.)

To all whom it may concern:

Be it known that we, ELI G. IVEY and MORGAN MCMICHAEL, of Buena Vista, in the county of Marion and State of Georgia, have invented a new and useful Flood-Gate, of which the following is a full, clear, and exact description.

This invention relates to an improved means for automatically controlling the height of water in a dam, and has for its objects to provide a simple, inexpensive device which can be applied to any dam located in a water-way and that will automatically graduate water-discharge from the dam, so as to maintain the water at a desired level and avoid an injurious overflow.

To these ends our invention consists in certain features of construction and combination of parts, as herein described and claimed.

Reference is to be had to the accompanying drawings, forming a part of this specification, in which similar letters of reference indicate corresponding parts in all the figures.

Figure 1 is a sectional side elevation of a dam having the improvement combined with it. Fig. 2 is a front view of the dam and flood-gate attachment, and Fig. 3 is a plan view of the device in position in a dam.

A represents the breast of a dam constructed across a stream or water-course to secure a proper head of water for use as a source of power. The height of the breast-wall A is such as will afford a proper retention of water within the dam for the driving of mechanism in the usual manner by means of water-wheels. (Not shown.) In the breast A of the dam suitable sluiceways are cut—one or more in number. Two of these sluiceways or water-discharge passages are shown at B, and at their sides guideways a are erected and firmly connected with the breast A of the dam.

The gates C are adapted to slide freely in the guideways a, wherein they are placed, the weight of said gates normally retaining them in place.

At a proper distance from the breast A, and within the dam a frame comprised of two upright posts b, connected by cross-timbers c, (see Fig. 3) are erected, the posts having sufficient height to extend to the surface of the water-line D, which represents the maximum of water-elevation within the dam.

Upon each gate C an upright arm d is secured, which latter are of such a relative height as to extend above the water-line D and be connected by the levers e with the top side of the float E. The float E, just named, is preferably constructed in cylindrical form, from sheet metal or wood, of sufficient capacity to contain a proper volume of atmospheric air, said float being made air-tight. The levers e are pivotally attached to the upper ends of the arms d on the gates C, and also are similarly connected to the top ends of the posts d by their opposite ends, the float E being firmly connected to the levers at such a point between their ends as will permit the gates C to remain closed and the float E rest on the water when the latter is at a normal elevation or level with the upper edge of the breast A of the dam.

During ordinary conditions of water fluctuation in the dam the gates C remain closed and the float E unmoved until, by reason of flooding of the water-shed that supplies the dam, an abnormal rise of water is occasioned. When there is such an increased volume of water accumulated in the dam as to flow freely over the breast A, the float E will be raised by the water and the gates C also.

After the flow of water through the gates C lowers the surface of the dam to an ordinary level, as represented by the line D, the gates will automatically close, so that all danger of injury which might result from a sudden abnormal increase in water-volume will be thus obviated by the operation of the device, which is in effect a water-governor that controls the water-supply within a dam and discharges surplus water accumulations in the same without manual attendance.

Having thus described our invention, what we claim as new, and desire to secure by Letters Patent, is—

1. The combination, with a sluiceway in a dam and a gate that is adapted to slide in the sluiceway, of a horizontal lever connected at its forward or downstream end to the gate, a float secured to the lever between its ends, the rear end of the lever being pivoted to a suitable support, substantially as set forth.

2. The combination, with a sluiceway in a water-dam, a vertically-movable gate in the sluiceway, and an arm secured on the gate, of

a horizontal lever pivoted to the gate-arm by one end, a vertical support for the other end of the lever, and an air-tight hollow float secured to the lever between its ends, substantially as set forth.

3. The combination, with a water-dam, sluiceways in the dam, and vertically-movable gates in the sluiceways, of an upright arm secured to each gate, a horizontal lever for each gate pivoted by one end to the gate-

arm, vertical posts, to which are pivoted the other ends of the horizontal levers, and a hollow air-tight float secured to the horizontal levers between the gates and the posts, substantially as set forth.

ELI G. IVEY.
MORGAN McMICHAEL.
